[57] CLAIM

The ornamental design for a facsimile, as shown and described.

DESCRIPTION

FIG. 1 is a right top perspective view of a facsimile showing our new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a bottom plan view thereof;

FIG. 8 is a left top perspective view thereof with the handset spaced apart from the console; and

FIG. 9 is a right top perspective view of FIG. 1, the broken line showings of sheets being environmental only and forming no part of the claimed design.
